Patented Apr. 27, 1920.

INVENTOR

Alfred N. Clough
BY John A. Fairsmith
HIS ATTORNEY

UNITED STATES PATENT OFFICE.

ALFRED N. CLOUGH, OF SUNNYVALE, CALIFORNIA, ASSIGNOR TO THREE LEAF COT MANUFACTURING CO., OF SUNNYVALE, CALIFORNIA, A CORPORATION OF NEVADA.

SPRING.

1,338,490.

Specification of Letters Patent. Patented Apr. 27, 1920.

Application filed August 18, 1919. Serial No. 318,276.

To all whom it may concern:

Be it known that I, ALFRED N. CLOUGH, a citizen of the United States, and resident of Sunnyvale, in the county of Santa Clara 5 and State of California, have invented certain new and useful Improvements in Springs, of which the following is a specification.

My invention relates to springs for use 10 upon beds, cots and similar structures.

It is the principal object of my invention to provide a spring having supporting elements so constructed and arranged as to give at the point of application or pressure 15 thereto and to conform substantially to the form of the body exerting the pressure, without materially altering the general level of the rest of the spring. Another object of the invention is to provide a device of 20 the character indicated having supporting elements so connected and arranged that pressure applied to one portion of the spring will exert tension strains upon the rest of the spring in such a manner as to increase 25 its resistance to loads applied thereto. Further objects are to provide a spring that will be light, strong, durable, simple in construction and that can be readily packed in small space.

30 The drawing is a plan view of a spring embodying my invention.

Referring more particularly to the drawing, 1 is a frame of any suitable form upon which the spring embodying my invention 35 is mounted. The numeral 2 indicates in each case a suitable supporting wire, cord or cable secured to one end of frame 1 and positioned parallel with the sides of said frame and extending a distance toward the 40 center thereof, the several wires being suitably spaced as shown. At 3 are shown similar wires alined with wires 2 in the center of frame 1 and connected at each end to the inner end of the adjacent wire 2 by a 45 spring as 4. At 5 are shown shorter wires than provided at 3, placed midway between wires 3 and parallel thereto and attached at each end to a spring 6. The length of each wire in conjunction with springs 6 is such 50 that wires 7 connecting the outer ends of springs 6 with the point of junction of springs 4 and wire 2 are angularly positioned with relation to wires 2, 3 and 5.

The several parallel wires 2 are jointed 55 as at 8 and connected at intervals by light

spacing wires 9 also jointed as at 10. Wires 2 are also connected to each other on a line adjacent springs 4 by a series of springs 11, and to the sides of frame 1 by wires 12. I prefer also to join the outer ends of the 60 outside springs 4 at their points of junction with wires 2, to the side portions of frame 1 as indicated at 13.

In a spring construction as described a pressure applied to certain wires 3 as indicated at 14 exerts tensional strains upon the corresponding springs 4 and 6. These strains are transmitted through the several members of the spring to the frame thereof as indicated by the arrows 15.

It will be seen from the above description that a load upon one portion of the spring tends to maintain the normal level of the rest of the spring and add to its sustaining powers as it places the several supporting 70 members thereof under greater tension. This spring also may be packed in small space as any number of required joints may be made in the same and its thickness is determined by the weight of the wire and 75 tension springs used, there being no supporting cables or compression springs required.

While I have herein shown and described the preferred embodiment of my invention, 80 it is understood that changes in form, construction, proportions and arrangement of the several parts, members and features may be made within the scope of the appended 85 claims.

I claim:

1. A spring including sustaining means, a plurality of tension members attached thereto and extending longitudinally thereof and having middle sections resiliently 95 mounted therein in alinement therewith, longitudinally disposed tension members arranged between said middle sections and resilient connections between said last mentioned tension members and said first mentioned tension members.

2. A spring including sustaining means, a plurality of tension members attached thereto and extending longitudinally thereof and having middle sections resiliently 105 mounted therein in alinement therewith, longitudinally disposed tension members arranged between said middle sections and resilient connections between said last mentioned tension members and said first men- 110

tioned tension members at the ends thereof adjacent their middle sections.

3. A spring including sustaining means, a plurality of jointed tension members attached thereto and extending longitudinally thereof and having middle sections resiliently mounted therein in alinement therewith, longitudinally disposed tension members shorter than said middle sections arranged intermediate said middle sections, tension members attached to the inner ends of said first mentioned tension members at their points of junction with their resiliently mounted middle sections, resilient means connecting each end of each of said

intermediately arranged members with the two adjacent last described tension members, resilient connections between the adjacent first mentioned tension members, jointed spacing members connecting said first mentioned tension members, and tension members connecting the outermost of said first mentioned tension members to said sustaining means at points in substantial alinement with said last mentioned resilient connections and at points in substantial alinement with the resilient connections of said members with their middle sections. 20 25

ALFRED N. CLOUGH.
